UNITED STATES PATENT OFFICE.

LEONIDAS N. LYON, OF SAN ANTONIO, TEXAS.

PROCESS OF TREATING WOOD.

1,382,103.

Specification of Letters Patent. Patented June 21, 1921.

No Drawing.

Application filed November 3, 1919. Serial No. 335,470.

To all whom it may concern:

Be it known that I, LEONIDAS N. LYON, a citizen of the United States, residing at San Antonio, in the county of Bexar and 5 State of Texas, have invented a new and useful Process of Treating Wood, of which the following is a specification.

It is the object of this invention to provide a novel method for treating wood. The 10 word "wood" is intended to cover the substances usually designated as timber, lumber, poles, posts, etc.

As to the "treating", the process relates primarily to the drying and preservation of 15 the wood, but it contemplates, also, the treating of the wood with an insecticide of some kind.

By way of explanation it may be stated that under the present practice, wherein 20 wood is dried in a kiln, the moisture in the wood is converted into steam by the application of heat up to a certain point, beyond which it is unsafe to heat the wood lest conflagration occur. The steam thus produced 25 collects to a greater or less degree within the kiln chamber, and condensation takes place, the moisture being again absorbed by the wood, to be reexpelled by the application of heat. It is obvious that a procedure of 30 the kind mentioned is time-consuming. The foregoing being understood, it may be stated that one object of this invention is to provide a novel process whereby when the moisture has been driven out of the wood, the 35 moisture will not be absorbed again by the wood.

In known processes, the wood is dried in kilns, and the wood comes from the kiln with its pores open and ready to take in 40 more moisture whenever the occasion presents itself. The processes hereinafter described aim to overcome this difficulty.

Carrying out the process contemplates a container filled with a substance the precise 45 composition of which may be varied, as occasion may demand. The substance may be a wax, such as mineral paraffin or, it may be tar, pitch or asphaltum. It may be an oil such as creosote oil, castor oil, or a combination 50 of oils, a combination of waxes, a wax and one or more oils, or an oil and one or

more waxes. In any event, the substance has a specific gravity greater than that of steam, the flaming point of said substance being above the vaporizing point of water. 55

Heat is applied to the container until the substance therein is brought to a higher temperature than the boiling point of water, and in the heated contents of the container, the wood to be treated is placed. The wood 60 is permitted to remain immersed in the heated substance until the moisture in the wood is converted into steam, the steam escaping through the substance wherein the wood is enveloped. Although the steam thus 65 escaping may condense, the water of condensation cannot be reabsorbed by the wood, for the reason that the heated substance in the container serves as an effective seal or barrier. Further, some of the oils and 70 resins in the wood will be heated and diffused through the wood, the result being that the wood will be preserved.

When the wood is removed from the container, the wood retains for a period of time, 75 a temperature approximately that of the heated substance from which the wood has been withdrawn. As a consequence, much of the heated substance will drain off the wood. If it is desired to retain a given 80 amount of the material in or on the wood, this result can be secured by quickening the cooling of the wood in any suitable way.

It may be desirable to apply an insecticide 85 to the wood and when this result is desired, the wood may be boiled in an insecticide, the flaming point of which is above the boiling point of water: or, if desired, an insecticide may be mixed with a wax or waxes, an oil or oils, or a combination of those substances. It is claimed, that the process hereinbefore described accelerates the drying and seasoning of the wood and aids in the 90 preservation thereof.

Having thus described the invention, what 95 is claimed is:

A method of treating wood which consists in raising the temperature of the body of liquid sealing and permeating medium to a point above the boiling point of water but 100 below the flaming point of the medium; immersing the wood, in a natural state, in the

medium, maintaining the wood immersed until the moisture in the wood is converted into steam and rises through the medium, and withdrawing the wood from the medium leaving the wood sealed by the medium to prevent a reabsorption of moisture.

In testimony that I claim the foregoing as

my own, I have hereto affixed my signature in the presence of two witnesses.

LEONIDAS N. LYON.
